UNITED STATES PATENT OFFICE.

HENRY J. BUBENHEIM, OF PITTSBURGH, PENNSYLVANIA.

RAILWAY-TIE AND RAIL-FASTENER.

1,275,656.

Specification of Letters Patent.

Patented Aug. 13, 1918.

Application filed January 31, 1916. Serial No. 75,228.

To all whom it may concern:

Be it known that I, HENRY J. BUBENHEIM, a citizen of the United States, residing at Pittsburgh, in the county of Allegheny and State of Pennsylvania, have invented a certain new and useful Improvement in Railway-Ties and Rail-Fasteners, of which the following is a specification.

This invention pertains to the art commonly known as rail ties and rail fasteners, and is more particularly defined and related to that class designated as metallic or so called steel ties, utilized in railway construction.

The fundamental idea involved is the simple and efficient fastening means I employ for securing the rail sections to the tie, without the necessity for using bolts, nuts, or kindred fastening equivalents, whereby a reliable and inseparable union will prevail between the tie and rail.

The tie proper may be of any desired configuration in cross section, no invention being claimed for the particular shape disclosed in the accompanying drawing, but I confine my invention to the novel fastening or locking feature employed in combination with the supporting tie structure.

In the accompanying drawing I have shown the preferred embodiment of my invention, which however, is susceptible of modification in the detail form of construction, without materially altering the basic idea involved, and I therefore do not limit myself to the exact arrangement herewith disclosed, but reserve the right of making such changes as may be later on found more expedient, without departing from the original idea and intention.

Referring then to said drawing Figure 1 is a plan view of the tie in broken formation: Fig. 2 is a longitudinal section in elevation showing modified means for fastening the rail to the tie, this view being taken on the line 11—11 of Fig. 1: Fig. 3 is a plan view of the tapered key member: Fig. 4 shows a cross section on the line IV—IV of Fig. 3: Fig. 5 is a perspective view of one form of removable contact bar involving under disposed integral lugs, and Fig. 6 is a sectional view showing means for providing insulation between the rail and splice bars and chair,

The tie proper, which is illustrated as being of an approximate inverted T-bar configuration, with base flanges and vertical web, but may be of any other substitute shape, is designated as a whole by the reference numeral 1, and involves the laterally projecting integral extensions or spaced-apart rail chairs 2 and 3, respectively, comprising the base flanges 4 and web 5.

In the tie here disclosed two modified forms of fastening means are involved, the one at the left hand side being designed to grip the base flanges of the rail, thereby fastening said rail securely to the tie, while at the opposite right hand side provision is made for uniting the abutting ends of two rail sections, this portion serving as a joint or union, and involves splice bars which engage the rails in the usual well known manner.

Both rail chair portions of the tie are of an approximate channel formation, involving the inner disposed vertical walls between which the rail sections and fastening elements are removably confined. The bottom section of each chair is provided with apertures 6, preferably rectangular in shape, there being required two of these openings for the chair 2, and four of the same for the chair 3, as shown. The edges of these apertures nearest the longitudinal center of the chair are preferably beveled in order to permit free introduction of the angular lugs carried by the removable bar members.

Referring to the chair 2 separately, this portion has its outer wall, or that portion nearest the end of the tie, bent inward and forming an overhanging flange 8, which provides an under disposed longitudinal recess 9, designed to receive and house one side of the rail base. The opposite wall 10 is approximately perpendicular, or it may be made with a slight taper drawn to a vertical line, and is positively tapered longitudinally from end to end, the degree of taper being approximately one eighth inch to the foot, thereby varying the width of the channel recess accordingly. This wall 10 is recessed at 12, or adjacent the bottom edge for the full length of said wall.

After the rail has been placed on the tie and seated in the chair 2, with its base flange entered in the recess 9, the removable bar

member 13, shown in Fig. 5, is placed in its engaging attitude with the rail base. This said bar member is provided with depending lug portions 14, cut on an angle of approximately forty-five degrees, which enter the apertures 6 formed in the chair, and serve to prevent any longitudinal movement of the said bar; there also being provided on this bar member a longitudinal cut-out portion or ledge 15.

The next step in the assembling process consists in the insertion of the wedge key member 16 shown in Fig. 3 between the said bar 13 and tapered wall 10. This key element is of an approximate Z-bar configuration in cross section, involving the inner disposed projecting rim or flange portion 17, which registers with and seats on the ledge 15 formed in the said bar member, together with an outer disposed flange 18 that enters the recess 12 provided in the chair wall 10. Said key is tapered from end to end in conformity with the taper accorded the intervening space between the said bar 13 and chair wall 10, which gives to said key a wedging function for the purpose of insuring a positive locking and immovable attitude in conjunction with all the coöperating parts.

30 When this key is driven into its functional position from one end of the chair, its interlocked attitude with the wall 10 and bar 13 will prevent displacement of either the key or bar, no disassociation or removal 35 of the several parts being possible until after said key is driven out of its locking position.

The side of the key member 16 that engages with the chair wall 10 is further provided with one or more vertically disposed grooves or slots 19 that are intended to register with a similar shaped groove 20 formed in the chair wall at a convenient location, which permits the introduction of 45 a removable pin 21 that serves to secure and lock the tapered key against longitudinal movement.

In the event of it being found necessary to further drive in this locking key, in order to take up any slack or space incidental to wear of the respective coacting parts, said pin 21 is first removed, and after the driving in process is completed, it is again dropped into the receptive aperture provided by the registering grooves. With this foregoing described construction and arrangement of parts it will be practically impossible for the key to become loosened or to move out of its functional locking attitude with the coacting elements, thus insuring an efficient fastening device that will confine the rail section A securely to the tie.

Referring to the modified construction or

chair 3: This member which is likewise of a channel formation, involves the parallel side walls 10, each wall being provided with the longitudinal recess 12, there being also provided the oppositely disposed alining bottom apertures 6, which are positioned equidistant from the longitudinal center line of said channel. The walls of this chair are also tapered longitudinally, the taper on one side being in an opposite direction from that of the other side, in order that when the two splice bars 22 are placed in position the wedge keys may be driven in from opposite ends of the chair.

These aforesaid splice bars 22 are likewise provided with the under disposed angular lugs 14, which seat in the bottom apertures 6, also the outer marginal cut-out or ledge 15, and in addition the vertically disposed flange section, that lies in parallel alinement with the rail web, is provided on its inner face with one or more projecting studs or lugs 23 designed to enter a registering aperture formed in the rail web, said studs entering from both sides of the rail, their function being to prevent any material longitudinal movement of the secured rail sections. The diameter of said web apertures should be somewhat greater than the diameter of the entered studs 23, in order to allow for the natural expansion and contraction prevalent in the joint.

In order to provide for the free and uninterrupted insertion or positioning of the bar member 13, and likewise the splice bars 22, in their functional position within the associated chair, there is provided the marginal cut-outs or pockets 24, formed in the side walls of the chair, which are in registering alinement with the several bottom apertures 6, the lug portion of each bar readily entering through these said pockets and seating in their respective aperture. These said pockets also serve to expose a portion of the sides of the locking keys, whereby corrosion, and the accumulation of dirt or other foreign substance at this point, will aid materially in keeping these keys in their locking attitude, thus it will be found that said key, even after the locking pin 21 has been removed, will prove much harder to drive out of its seat than into the same.

In Fig. 6 I have shown means for providing adequate insulation 25 intermediate of the rail sections, splice bars, and chair, for a purpose well known in the art, this feature simply being utilized as a necessary adjunct to my improved tie, for which no invention is claimed.

Although the tie disclosed in the drawing involves two distinct forms of rail seats, each intended for their own specific pur-

pose, I desire it understood that my invention is not limited to this particular construction, but that the tie can be supplied with the form of chair 2 at both ends thereof, or it may have the other form 3 as a substitute, the latter form of seat only being required where it is necessary to unite the abutting ends of two rail sections, the intermediate ties being furnished with the rail seats 2 at both ends.

10 What I claim as my invention is:—

15 1. A railway tie and rail fastener having laterally extending rail seats of a channel formation, one wall of said channel being tapered longitudinally, the opposite wall being bent inwardly to form an overhanging flange for contact with the rail base, apertures in the bottom of said rail seats, and pockets in the channel wall which register with the bottom apertures.

20 2. A railway tie and rail fastener having laterally extending rail seats of a channel formation, one wall of said channel being tapered longitudinally and provided with a recess, the opposite wall being bent inwardly to form a contact flange and receptive recess for the rail base, apertures in the bottom of said rail seats, and pockets in the channel wall which register with the bottom apertures.

25 3. A railway tie and rail fastener having laterally extending rail seats of a channel formation, one wall of said channel being tapered longitudinally and provided with a recess, the opposite wall being bent inwardly to form a contact flange and receptive recess for the rail base, apertures in the bottom of said chair, pockets in the channel wall which register with the bottom apertures, a removable bar member seated in the chair and engaging one side of the rail base, said bar being provided with lugs which enter the bottom apertures, also with a longitudinal marginal ledge, and a tapered key member adapted to be driven in between the tapered wall and bar, said key having means formed thereon and coöperating with the tapered wall and bar member for locking said key in position.

30 4. A railway tie and rail fastener having laterally extending rail seats of a channel formation, one wall of said channel being tapered longitudinally and provided with a recess, the opposite wall being bent inwardly to form a contact flange and receptive recess for the rail base, apertures in the bottom of said chair, pockets in the channel wall which register with the bottom apertures, a removable bar member seated in the chair and engaging one side of the rail base, said bar being provided with lugs which enter the bottom apertures, also with a longitudinal marginal ledge, and a tapered key member adapted to be driven in between the tapered

35 wall and bar, said key having a flange which enters the recess provided in the chair wall, also having a second flange to seat on the ledge formed in said bar member.

5. A railway tie and rail fastener having laterally extending rail seats of a channel formation, the walls of said channel being tapered longitudinally and each being provided with a longitudinal recess; apertures in the bottom of said chair; pockets in the channel wall which register with the bottom apertures, removable splice-bars seated in the chair and engaging the rail sections, said bars being provided with lugs designed to enter the bottom apertures, also with a marginal ledge; and tapered keys adapted to be entered and wedge between the said splice bars and walls of the chair, said keys having means formed thereon for an interlocking engagement with the wall recess and ledge provided on the abutting splice bar.

6. A railway tie and rail fastener having laterally extending rail seats of a channel formation, the walls of said channel being tapered longitudinally in opposite directions to each other and each wall being provided with a longitudinal recess; apertures in the bottom of said chair; removable splice bars seated in the chair and engaging the rail sections, said bars carrying depending lugs designed to enter the bottom apertures, also having additional lugs for entry through the rail web, said bars each being further provided with a marginal ledge; tapered keys adapted to be entered and wedge between the said splice bars and walls of the chair, said keys each being provided on one side with a flange to enter the wall recess, and on the opposite side with a second flange to seat on the ledge formed in the contacting splice bar; a groove formed in each wall of the channel adapted to register with a similar shaped groove formed in the side wall of said tapered key member; and a removable locking member designed to seat in said registering grooves.

7. A railway tie and rail fastener having laterally extending rail seats of a channel formation, the walls of said channel being tapered longitudinally in opposite directions to each other and each wall being provided with a longitudinal recess; apertures in the bottom of said chair; pockets formed in the channel walls in registering alinement with the bottom apertures; removable splice bars seated in the chair and engaging the rail sections said bars carrying depending lugs designed to enter the bottom apertures, also having additional lugs for entry through the rail web, said bars each being further provided with a marginal ledge; tapered keys adapted to be entered and wedge between the said splice bars and walls of the chair, said keys each being provided

on one side with a flange to enter the wall recess, and on the opposite side with a second flange to seat on the ledge formed in the contacting splice bar; a groove formed in the side wall of said tapered key member designed to register with a similar shaped groove formed in the channel wall; and a

removable locking member designed to seat in said registering grooves.

In testimony whereof I affix my signature 10
this 8th day of December, 1915.
